UNITED STATES PATENT OFFICE.

WARREN W. CARPENTER, OF QUEENS, NEW YORK, ASSIGNOR TO WESTERN ELECTRIC COMPANY, INCORPORATED, OF NEW YORK, N. Y., A CORPORATION OF NEW YORK.

RESTRICTED-SERVICE AUTOMATIC TELEPHONE SYSTEM.

Application filed October 11, 1923. Serial No. 667,796.

To all whom it may concern:

Be it known that I, WARREN W. CARPENTER, a citizen of the United States, residing at Queens, in the county of Queens and 5 State of New York, have invented certain new and useful Improvements in Restricted-Service Automatic Telephone Systems, of which the following is a full, clear, concise, and exact description.

10 This invention relates to automatic telephone exchange systems and more particularly to systems involving private branch exchange working.

Its object is to provide an improved circuit arrangement for restricted service lines; that is, lines from which connections can be set up automatically with other private branch exchange lines, but when the outgoing or central office trunk group is selected 20 from such lines, busy tone is sent back to the subscriber attempting to set up the prohibited connection.

In accordance with this invention, each connecting circuit is provided with a test 25 relay which, when the calling line is automatically extended to the connecting circuit upon the initiation of the call is connected to and tests for an electrical condition on one of the calling line terminals 30 which condition is permanently applied only to lines of one class, for example, non-restricted lines, and operates if such condition is present to control the electrical condition of the test brush of the first selector 35 to determine whether it will seize an idle trunk in the main-office level or pass over all the trunks in the level irrespective of their busy or idle condition. The operation of this relay on local trunk levels has 40 no effect on the trunk hunting operation.

Referring to the drawings:

Fig. 1 shows a calling subscriber's line and an automatic line finder switch and

Fig. 2 shows a selector, a connector and the called line.

The line finder is of the Strowger step-by-step type and is equipped with two banks and two sets of brushes, one hundred lines terminating in each bank. The lines are 50 in ten groups, corresponding to the ten ver-

tical positions of the switch. Each group therefore contains twenty lines, ten in the upper and ten in the lower bank. Every rotary position of the switch therefore embraces two lines of a group, one in the upper bank and one in the lower, and the connection is established with but one of the two; i. e., that one which is calling. 55

The invention will be most readily understood from a detailed description of the 60 operation.

The initiation of a call in line X or Y operates the corresponding line relay LR, L'R'. This causes the operation of group 65 relay G. Relay G at its armature 166 grounds the start wire 100 and at its armature 133 grounds commutator terminal 101 corresponding to the calling group. Relay A now operates as follows: ground, 166, 100, 168, 102, 103, A, battery. Relay A disconnects the brushes of the line finder from the tip and ring conductors 104, 105, to prevent interference and energizes the impulse relay A' of the first selector (Fig. 2) 70 as follows: ground, 106, 107, 120, 108, 109, 110, 111, 105, 201, A', battery. A' operates slow-to-release relay B', which interposes a break in the line finder release circuit and prepares the circuits of the first selector 75 to receive the setting impulses. Relay A also starts the vertical hunting movement of the finder by operating relay C as follows: battery, C, 112, 113, 114, 115, 116, 117, 118, 119, 120, 107, 106, ground. Relay C closes the following circuit for the vertical magnet 80 121: battery, 121, 122, 123, 124, 125, 126, 127, 108, 107, 106, ground. The vertical magnet at the end of the stroke of its armature 114 opens the circuit traced for relay C, which in releasing its armature 124, opens 85 the circuit of the vertical magnet. This well known cycle continues until the group brush 128 reaches the calling group commutator segment 101, and the ground on this segment holds the relay C energized over the 90 following circuit and thus arrests the switch: battery, C, 112, 113, left winding of relay E, 129, 139, 130, 131, 128, 101, 132, 133, ground. Relay E, which is slow to release, operates in this circuit and locks 95 100

as follows: battery, vertical magnet 121, 122, 125, 150, 151, 152, right winding of relay E, 127, 108, 120, 107, 106, ground. Relay E connects the commutator ground to the 5 rotary magnet 134 to operate the same to rotate the brushes into the bank and begin testing the lines of the calling group of twenty lines. The circuit for said magnet 134 is as follows: battery, 134, 135, 136, 10, 137, 138, 139, 130, 131, 128, 101, 132, 133, ground. Magnet 134 at the end of its stroke opens the circuit of relay C. The test terminals S, S' of all lines are normally grounded at the right hand armatures 161, 15, 147, etc. of their line relays. The upper and lower lines are tested simultaneously. If both are non-calling, ground on the upper test terminal S short circuits relay F at point 140 and operates relay C. The 20 circuit for relay C is as follows: battery, C, 112, 113, 114, 115, 155, 140, 156, 157, 158, 159, S, 160, 161, ground. Ground on the lower test terminal S' short circuits relay D at point 141, and operates the rotary 25 magnet 134 to move the brushes off these two non-calling lines. This circuit is as follows: battery, 134, 135, 136, 141, 142, 143, 144, S', 145, 146, 147, ground. The rotary magnet on attracting its armature 154 locks 30 itself to ground over 135, 136, 141, 137, 154, 118, 119, 120, 107, 106; and at the end of the stroke of its armature 113 opens the circuit of relay C, which in releasing its armature opens the circuit of magnet 134. This 35 cycle continues as long as grounded or non-calling terminals S, S' are encountered by the finder sleeve brushes 159, 144. When a calling line is reached the test circuit acts as follows: Assuming S only is ungrounded, 40 that is to say, line X is the calling line, relay C fails to operate since no ground is present on S, and therefore no circuit is closed for the rotary magnet 134 to the ground on sleeve multiple S' and consequently the finder stops. The absence of 45 ground on sleeve S causes relay F to operate as follows: battery, C, 112, 113, 114, 115, 155, 140, F, 162, 163, 164, 165, ground. Relay C is marginal and will not operate 50 in this circuit.

When relay F operates a test circuit is closed to the calling line to determine whether it is restricted or non-restricted. This circuit is as follows: battery, A, 103, 55 174, 175, right winding of B, 176, 177, 172, to the tip terminal T of the calling line. If the line is non-restricted a conductor 178, as shown in connection with line X, connects the normally grounded outer right 60 armature of cut off relay CO to the said tip terminal. If restricted, this conductor is absent, as, for example, as shown in connection with line Y. Relay B operates in the case of line X and locks to ground at 65 165 by its left winding over its left con-

tact and conductor 164. Relay B at its inner right armature removes ground at the back contact of release magnet 192 from conductor 180, which ground would otherwise prevent the subscriber from securing 70 a trunk on certain levels of the first selector, as will appear, and said armature applies said ground over 184, 185, 156, 157, 158, 159, S, 186, 193, CO, battery. Relay CO at its right armatures disconnects the 75 line relay LR, which releases the group relay G and at its left armature locks itself to said ground. Relay LR is slow to release to give the relay CO time to operate and lock. Relay CO in removing ground from 80 conductor 178 opens the circuit of relay A, which releases. Relay A in releasing restores the continuity of the tip and ring conductors 104, 105, and since relay D is inert, said conductors connect the tip and 85 ring terminals TR, and consequently the calling line X to the first selector (Fig. 2). Relay B at armature 151 opens the locking circuit traced including the right winding of relay E, which thereupon releases. 90

Assuming now that line Y had called instead of line X, terminal S' instead of S would have been ungrounded. Although relay C operates in this case due to ground on S, as described, and at its armature 136, connects the rotary magnet to terminal S', this magnet does not operate since no ground is present on terminal S'. Owing to the absence of ground on S', there is no shunt about the brush shifting relay D, and it operates as follows: battery, rotary magnet 134, 135, 136, 137, 138, 139, 130, 131, 170, D, 171, 116, 117, 118, 119, 120, 107, 106, ground. The rotary magnet 134 will not operate in this circuit. Relay D in attracting its armature 158 opens the short circuit described about relay F, which thereupon operates as described to connect relay A to the tip conductor in series with relay B to test for ground on the tip T' of the calling line Y and not finding such ground relay A releases, which in turn releases relay E. Relay D at its innermost lower armature closes a locking circuit for itself including conductor 164 and the off-normal switch 165. At its armatures 172, 173, relay D connects the tip and ring conductors 104, 105 to the brushes resting on terminals T' R' and thus extends the calling line Y to the first selector (Fig. 2). 110

If both lines X and Y are calling, the finder stops and preference is given to line X. In this case both sleeve terminals S and S' are ungrounded. Due to S being ungrounded, C fails to operate, as described, and F operates instead just as in the case described where line X alone was calling. The other operations are the same as those described where line X alone was calling. 125

When the calling line is restricted, no 130

ground is connected to the tip terminal, as in the case of line Y. Relay B therefore fails to operate and relay A immediately releases, applying ground as follows to operate cut-off relay O'O'; ground, 106, 187, 143 and its front contact, relay D being operated, 188, 144, S', 145, 189, 190, C'O', battery. Relay O'O' operates to cut off the line relay L'R' and at its left armature 10 locks itself to said ground.

In the case of a restricted line in the row engaged by the upper set of brushes, the circuit for operating the cut-off relay of such line does not lead over the front contact of relay B, as described for line X, since in such case relay B is not operated, but the circuit is as follows: ground, 106, 187, 169, 156, 157, 158 and its back contact, D' being inert, 159, S, to battery through the cut-off 20 relay of that line.

In the case of a non-restricted line in the row engaged by the lower set of brushes, the circuit for operating the cut-off relay of such line does not lead over the back contact of relay A, as described for line X, since in such case relay B is operated, but the circuit is as follows: ground at the back contact of release magnet 192, inner right armature and front contact of relay B, 184, 169, 143 and its front contact, relay D being operated, 188, 144, S', to battery through the cut-off relay of such line.

Assuming the line connected to by the finder to be line X, the impulse relay A' and slow relay B' of the first selector were operated when relay A was operated on the initiation of the call, as described. When relay A released, the impulse relay was held energized over line X by the continuity contacts of relay A. Relay A' now follows the dial impulses from line X, and each time it releases, ground from the uppermost armature and back contact of relay D' is applied to operate the vertical magnet 202 in series with slow relay C', which remains energized during the impulses. The vertical magnet steps the brushes 203, 209, 207 to the proper level. On the first vertical step, the off-normal switch 204 is operated and relay E' is energized over the alternate contact of relay C' to prepare the rotary stepping circuit in the well known manner. After the completion of dialing, relay C' releases but relay E' remains locked up over its left armature, to ground at the uppermost armature and normal contact of relay D'. Relay C' in releasing closes a circuit through the right armature and alternate contact of relay E' to operate the rotary magnet, which 55 steps the brushes 203 onto the first trunk terminals 206, 210, 208, and by unlocking relay E' is itself deenergized. If this trunk is busy, its sleeve terminal 208 is grounded, which shunts relay D' and reoperates relay 60 E' in the well known manner. The rotary 65

magnet is again operated and the operations just described are repeated until an idle trunk is found, which, having an ungrounded sleeve, relay D' is unshunted and operates in series with relay E' in the well known manner, the latter remaining inert due to its marginal adjustment. Relay D' closes the talking circuit and sleeve circuit through to the brushes 203, 209, 207, and cuts off relay A'. Relay D is now locked to the sleeve terminal, which is held grounded from the connector in the well known manner. If all trunks are busy the brushes are stepped to the eleventh position and a set of cam springs 211 operates and substitutes busy tone from source BT for the ground on the winding of relay A' applied through the secondary of dial tone source DT. Source DT is connected to the line as soon as relay A in the line finder operates, to inform the subscriber the circuits are ready for dialing.

When the calling line is refused connections on certain levels of the selector, the ground heretofore referred to applied to conductor 180, is extended by switch 213 closed on these levels by the switch shaft to the test brush 207, and this results in the selector operating as though it found all the trunks in this level busy, and returns a busy signal to the calling party from the all trunks busy source B. T.

When the selector brushes 203, 209, 207 pick out an idle connector, the impulse relay 214 thereof is operated to set the same on the desired line in the well known manner. 100 Battery for talking purposes is fed to the calling line through relay 214 and to the called line T through relay 215.

The release is controlled by the calling party, and upon his replacing the receiver, relay 214 releases and removes holding ground from the sleeve wire, which releases the connector in the well known manner. The removal of this ground, by releasing relay D', closes the circuit of release magnet 216 in the well known manner to restore the selector.

The line finder is released by the ground applied to release control conductor 191 due to the release of relay D'. This ground is applied over the uppermost armature of relay D', armatures and back contacts of relays B', A', conductor 191, off-normal switch 165, to the left winding of relay B to battery in the case of a restricted line, such as Y. If the calling line is nonrestricted, relay B is locked at this time to off-normal switch 165. Relay B locks to ground at off normal switch 165, and at its inner left armature applies the ground on conductor 191 to relay A. Relay A disconnects the talking brushes from the trunk during release to prevent interference, and closes the following circuit to the release magnet 192: battery 192, 151, 150, 125, 126, 127, 108, 120, 115 120 125 130

107, 106, ground. The release magnet armature applies ground to conductor 164 to close a second locking circuit for the left winding of relay B independently of ground at 165 and this ground also closes a second circuit for relay F to hold the same operated independently of its energizing circuit traced to ground at off-normal switch 165. When the shaft restores, off-normal switch 165 by 10 opening its uppermost contact restores relay A. Relay A in releasing opens the circuit of the release magnet. The release magnet in retracting its armature opens the locking circuit of relay B. The retraction 15 of the release armature also opens the holding circuit through the left winding of relay F.

Relay 195 is provided to disconnect the group relays G from battery when all the 20 finders are busy. This relay is operated by a circuit including the armatures 196 and front contacts of relays F of the operated finders in series, as shown and described in detail in Patent No. 1,278,245 of September 25 10, 1918 to A. B. Sperry.

The called multiple terminals of line X are shown at 199 and the line X is also multiplied to a jack 197 before an operator, who may extend calls to the line by the plug 30 198. When a connection is made to the line at either set of multiples, the cut-off relay CO operates to cut off the line relay LR to prevent starting a finder upon the response of the called party.

85 What is claimed is:

1. In a telephone system, telephone lines of different classes, means for establishing different electrical conditions on the terminals of one of the talking conductors of certain of said classes of lines, selectors having groups of trunks, means automatically operated upon the closure of the calling line for extending the line to an idle selector, means controlled by the calling party for setting 40 said selector to any trunk group, means thereupon automatically operated for driving the selector over the trunk group, a switch closed by the selector when set to a certain group, and means jointly controlled 45 by the electrical condition of the calling line terminal and said switch for determining whether the selector shall select an idle trunk or pass over idle trunks when set to the said group.

55 2. In a telephone system, telephone lines of different classes, means for establishing different electrical conditions on the terminals of one of the talking conductors of certain of said classes of lines, selectors having groups of trunks, means automatically operated upon the closure of the calling line for extending the line to an idle selector, means controlled by the calling party for setting 60 said selector to any trunk group, means thereupon automatically operated for

driving the selector over the trunk group, a switch closed by the selector when set to a certain group, means jointly controlled by the electrical condition of the calling line terminal and said switch for determining 70 whether the selector shall select an idle trunk or pass over idle trunks when set to said group, and means operated at the end of the travel of the selector for transmitting a tone to the calling party. 75

3. In a telephone system, telephone lines of different classes, means for establishing different electrical conditions on the terminals of said classes of lines, selectors having groups of trunks, means automatically operated upon the closure of the calling line for extending the line to an idle selector, means controlled by the calling party for setting 80 said selector to any trunk group, means thereupon automatically operated for driving the selector over the trunk group, a ground connection, a switch closed by the selector when set to a certain group to connect said ground to the selector test brush, means in said selector actuated by the presence of said connection for preventing the selector from seizing an idle trunk when set to said group, and a relay operated only on a call from one class of lines for preventing 85 the extension of said ground connection when said switch is actuated. 90

4. In a telephone system, restricted lines, non-restricted lines, selectors having trunk groups, a finder for automatically extending a calling line to an idle selector upon the closure of the calling line circuit, each non-restricted line having a terminal therein connected to one pole of the battery and the corresponding terminal of the restricted lines being disconnected from battery, a relay associated with the finder and operated only when the finder extends a non-restricted line, means for setting said selector to any trunk group and for automatically driving the same thereover, a ground connection, a switch closed by the selector on a given level to extend said ground to the selector test brush, means in said selector actuated by the presence of said ground connection for preventing the selector from seizing an idle trunk when set to said group, and a relay operated only on a call from non-restricted 100 lines for preventing the extension of said ground connection when said switch is actuated. 105

5. In a telephone system, restricted lines, non-restricted lines, selectors having trunk groups, finders for automatically extending calling lines to idle selectors upon the closure of the calling line circuits, a talking terminal of each non-restricted line in the finder being grounded, means for setting said selector to any trunk group and for driving the same thereover, means for causing the selector to select the first trunk whose test 110 115 120 125 130

terminal is ungrounded, a switch closed by the selector when set to a given level, a ground connection applied to the selector test brush by way of said switch when said 5 level is selected for applying ground to the test terminals in said level as the selector passes over them to prevent any trunk therein from being seized, a test relay associated

with the finder and operated when a non-restricted line is extended for preventing 10 said switch from extending said ground connection to said test brush, and a locking circuit for said relay.

In witness whereof, I hereunto subscribe my name this 3rd day of October, A. D. 1923.

WARREN W. CARPENTER.
